UNITED STATES PATENT OFFICE.

GEORGE E. SAVAGE, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A COVER FOR DISHES.

No. 38,285.

Specification for Design.

Patented Oct. 16, 1906.

Application filed August 22, 1906. Serial No. 331,658. Term of patent 7 years.

To all whom it may concern:

Be it known that I, GEORGE E. SAVAGE, a citizen of the United States, residing at Meriden, county of New Haven, State of Connecticut, have invented a certain new, original, and ornamental Design for Covers for Dishes, of which the following is a specification, reference being had to the accompanying drawing, forming part thereof.

The figure is a perspective view of a cover for dishes, showing my new design.

I claim—

The ornamental design for a cover for dishes, as shown.

GEORGE E. SAVAGE.
